UNITED STATES PATENT OFFICE.

HOMER KERN AND JOHN R. PATTISON, OF GERMANTOWN, OHIO.

CONCRETE FLOWERPOOT MACHINE.

Application filed January 30, 1925. Serial No. 5,836.

To all whom it may concern:

Be it known that HOMER KERN and JOHN R. PATTISON, citizens of the United States, residing at Germantown, in the county of 5 Montgomery and State of Ohio, have invented certain new and useful Improvements in Concrete Flowerpot Machines, of which the following is a specification.

This invention relates to new and useful 10 improvements in concrete flowerpot machines.

The primary object of our invention is to provide a rapid method of forming, packing and finishing concrete flower pots at one 15 operation.

With the foregoing and other objects in view that will appear as the nature of our invention is better understood the same consists in the novel features of construction, 20 combination and arrangement of parts illustrated in the drawings and more particularly pointed out in the appended claims.

In the accompanying drawings which are for illustrative purposes only and are therefore 25 not drawn to scale:

Figure 1 is a front elevation of a concrete flower pot machine embodying our improvements.

Figure 2 is an end view.

Figure 3 is a plan view.

Figure 4 is a detail longitudinal section.

Figure 5 is a horizontal section.

Figure 6 is a sectional view of the packer.

Figures 7, 8 and 9 are details of various 35 features of our invention.

Referring to the drawings for a more particular description of our invention and in which drawings like parts are designated by like reference characters throughout the 40 several views, our machine comprises an upright frame A consisting of the upright and cross bars 1 and 2, respectively, and the base or platform 3. Numeral 4 designates the mold which is supported upon the 45 horizontal table 5 and conforms to the outside measurements and contour of standard flower pots. It will be understood of course that any suitable form or design of mold may be employed to manufacture corresponding flower pots. The packer 6 is carried by the lower end of the perpendicular shaft 7 mounted in bearings 8 and this shaft is provided at its upper end with a longitudinal key-way 9 in which is slidably mounted a key 10 carried by the pulley 11. A motor 12 is mounted on the base 3 and

rotary motion is transmitted from said motor to said shaft by the following gearing. A belt 13 runs over the pulley 14 of the motor and over a larger pulley 15 carried by 60 the horizontal shaft 16 journaled in bearings 17 above the base. A second pulley 18 is mounted on the shaft 16 and is connected with the pulley 11 by the endless belt 19 which works over the idlers 20 keyed to the 65 horizontal shaft 21 journaled in bearings 22 mounted on the frame A above the shaft 16. A rock shaft 23 is journaled in bearings 24 in the frame A at a point preferably between the shafts 16 and 21 and is 70 provided at its forward end with a fork 25 connected by a collar 26 with the perpendicular packer shaft 7. One end of the rock shaft 23 is provided with a depending crank handle 27 which extends downwardly to 75 within convenient reach of the operator and whereby the shaft 7 may be raised or lowered to engage or disengage the packer with the mold 4. In this connection attention is called to the fact that the longitudinal key-way 9 in shaft 7 permits vertical movement 80 of the latter with respect to the pulley 11 without interfering with the rotary movement of said shaft. The packer comprises a central substantially cylindrical core 28 85 and a pair of oppositely disposed downwardly flared arcuate packing segments 29, connected with the core by the curved webs 28' and whose surfaces from a to b are formed on the arc of a circle of greater 90 diameter than from b to c. In other words, the surfaces of the packing segments from a to b are concentric with the rim 29' and from b to c eccentric thereto. The rim 29' is formed at the upper end of the case 28 95 and this case is provided with a boss 31 which projects above the aforesaid rim and is provided with a central bore 32 adapted to receive the lower end of the perpendicular shaft 7. The packer is attached to this shaft 100 by the set screw 33 or other equivalent means. Attention is invited to the fact that the bottom of the packer is formed with a pair of arcuate oppositely disposed reversely extending grooves 34; also, that the bottom 105 wall of the rim is formed with an annular groove 30.

In practice, Portland cement mixed in the proper proportions with sand and water is introduced into the mold. The packer, rotating in a counter clock-wise direction at a speed of approximately two hundred revo-

lutions per minute is then lowered into the mold when the material in the bottom of the mold is worked up towards the top and sides of the mold at the same time by virtue of 5 the peculiar shape of the grooves 34 formed in the bottom of the packer, and that of the packing segments 29. The packer is gradually lowered into the mold until the molding operation is completed, that is to say, 10 until a complete flower pot is molded, and at the completion of this molding operation the recessed bottom edge of the rim 29' of the packer is located one-eighth of an inch below the top of the mold. The mold 15 is provided with a false bottom 35 having one-eighth of an inch play and when the mold is inverted on a smooth surface and pressure applied to the false bottom 35, the finished flower pot is released from the mold 20 and will rest on the pallet.

It will be understood that all sizes and designs of flower pots may be manufactured by using corresponding molds and that the packers and molds may be used in 25 single or multiple. It is claimed that on account of the spinning motion of the packer that the inside of the flower pot is very smooth when finished; also that the use of our false bottom 35 for the mold permits 30 the finished flower pot to be released on the pallet in a more moistened condition than by any method now employed.

From the foregoing description taken in connection with the drawings, it is thought 35 that the construction, operation and advantages of our invention will be readily under-

stood without requiring a more extended explanation.

Having described our invention, what we claim as new and desire to secure by Letters Patent, is:—

1. In a device of the character specified, a mold and a packer cooperating therewith in forming flower pots, said packer comprising a central core and a pair of oppositely disposed downwardly flared arcuate packing segments, the bottom of the packer formed with a pair of arcuate oppositely disposed reversely extending grooves and the top of the packer with a circular rim formed 45 in its bottom wall with an annular groove or depression, substantially as and for the purpose specified.

2. In a device of the character specified, a mold conforming to the general outside 55 shape of a flower pot, a packer comprising a cylindrical downwardly flared body portion formed in its bottom with a pair of arcuate oppositely disposed reversely extending grooves, a circular flange formed at the 60 top of the body portion of the packer and formed in its bottom wall with an annular groove and a false bottom for the mold having vertical play, the bottom wall of the packer flange fitting below the upper edge of the mold at a distance corresponding to the vertical play of the false bottom at the completion of the molding operation.

In testimony whereof they affix their signatures.

HOMER KERN.

JOHN R. PATTISON.
